(57) **CLAIM**

What is claimed is a ring handle for a bag, as shown and described.

DESCRIPTION

FIG. 1 is a front view of a ring handle for a bag.

FIG. 2 is a rear view of the ring handle for the bag of FIG. 1.

FIG. 3 is a left side view of the ring handle for the bag of FIG. 1.

FIG. 4 is a right side view of the ring handle for the bag of FIG. 1.

FIG. 5 is a top view of the ring handle for the bag of FIG. 1.

FIG. 6 is a bottom view of the ring handle for the bag of FIG. 1; and,

FIG. 7 is a perspective view of the ring handle for the bag of FIG. 1.

The broken lines showing a handbag and other handbag elements are for the purposes of illustrating environment and form no part of the claimed design.
